COMBINED FOOD PATTY MOLD AND PRESS MEMBER

Julian G. Wright, Rte. 1, Box 757,
Splendora, Tex. 77372

Filed Oct. 10, 1972, Ser. No. 295,809

Term of patent 14 years

Int. Cl. D7—02

U.S. Cl. D7—43

fig.2

FIG. 1 is an isometric view of the top, front, and one side of a combined food patty mold and press member showing my new design, the rear and other side being identical to that shown.

FIG. 2 is a sectional elevation taken along line 2—2 of FIG. 1.

FIG. 3 is an isometric exploded view thereof.

I claim:

The ornamental design for a combined food patty mold and press member, as shown and described.
